(57) **CLAIM**

The ornamental design for a lamp, as shown and described.

DESCRIPTION

FIG. 1 is a perspective view of a lamp showing my design.
FIG. 2 is a front elevation view thereof.
FIG. 3 is a back elevation view thereof.
FIG. 4 is a left elevation view thereof. The right elevation view is omitted because it is symmetrical to the left elevation view.
FIG. 5 is a top plan view thereof; and,
FIG. 6 is a bottom plan view thereof.
Color forms no part of the claimed invention.
Although usable in other ways, the lamp is intended to be used for illumination of spaces.
